INVENTOR

CARL WINKLER

BY *Alvin H.*

ATTORNEY

UNITED STATES PATENT OFFICE.

CARL WINKLER, OF BERNE, SWITZERLAND.

MOLD FOR CASTING RIBBED STEREOPLATES.

Application filed March 21, 1923. Serial No. 626,595.

To all whom it may concern:

Be it known that I, CARL WINKLER, a citizen of the Swiss Republic, residing at Berne, in the Swiss Republic, have invented 5 a new and useful Improved Mold for Casting Ribbed Stereoplates, of which the following is a specification.

In using water for cooling the core of the mold or box used for casting stereoplates 10 having ribs on the back it is sometimes possible to trace the ribs on the front of the plate. This is due to the fact that the ribs on the outside of the core, by which the ribs on the plate are formed, cause the wall to have a 15 varying thickness, so that the plate is not uniformly cooled.

According to my invention this drawback is overcome by providing grooves on the inside of the core-wall, between the grooves on 20 the outside, so that the wall has the same thickness at all parts.

On the drawing illustrating the invention by way of example Fig. 1 is a longitudinal section, and Fig. 2 a cross section, of a mold 25 for casting stereoplates.

The mold for stereoplates consists of the

core *a*, bed *b*, side rings *c* and matrix *d*. On the outside of the core are the usual grooves *e* for forming the plate ribs, and, on the inside of the core, there are grooves *f*, according to the invention, which are between the grooves *e* and have such a shape that the wall of the core has approximately the same thickness throughout.

A further advantage of the grooves *e* and *f* is that the cooling surface is much increased.

What I claim and desire to secure by Letters Patent of the United States is:

In a mold for casting ribbed stereoplates 40 the provision of grooves on the outside of the wall of the core, and grooves on the inside of said wall, between said outside grooves, substantially as, and for the purpose, set forth.

In testimony whereof I have signed my name to this specification in the presence of 45 two subscribing witnesses.

CARL WINKLER.

Witnesses:

SAMUEL GEORGE TRIPP,
R. HEINGARTNER.
